DEVICE FOR PRODUCING STIMULATED INFRARED EMISSION, IRASER, BY MEANS OF AN ELECTRIC DISCHARGE IN A GAS MIXTURE CONSISTING AT LEAST PARTLY OF CARBONIC ACID AND DISCHARGE TUBE FOR SUCH A DEVICE

The invention relates to a device for producing stimulated infrared emission, an iraser, by means of an electric discharge in a gas mixture consisting at least partly of carbonic acid in a circular cylindrical quartz tube, the electrodes being arranged laterally of the iraser resonator.

In the device known from Dutch Patent application No. 6,509,730 the electrodes are arranged in side tubes of the discharge space.

The discharge path in the resonator space therefore does not extend symmetrically at the ends. This has an unfavorable influence on the mode pattern and the irradiated power.

It is the object of the invention to provide a construction which avoids the above drawbacks.

According to the invention, a device is provided for producing stimulated infrared emission, an iraser, by means of an electric discharge in a gas mixture consisting at least partly of carbonic acid in a circular cylindrical quartz tube. The electrodes are arranged laterally of the iraser resonator and consist of circular-cylindrical rings which are arranged coaxially with the discharge space on the outside of the quartz tube. The rings surround a circumferential interruption in the quartz tube with wider quartz tubes surrounding the electrodes and connecting the interrupted parts together in a vacuumtight manner.

The interruption in this construction need be only narrow, less than 1 mm. because the current intensity usually is less than 100 mA. At the total pressure of approximately 10 Torr. the discharge current distributes regularly over the whole circumference of the interruptions so that the whole cross section of the tube contributes evenly to the discharge and a favorable symmetrical mode pattern is obtained. As a result of the narrow interruption, very little sputtering occurs inside the discharge space.

In order that the invention may be readily carried into effect, one embodiment thereof will now be described in greater detail, by way of example, with reference to the accompanying drawing, in which

FIG. 1 diagrammatically shows a discharge tube according to the invention, and

FIG. 2 shows a part thereof at a given stage of the manufacture on an enlarged scale.

Referring now to FIG. 1, reference numeral 1 denotes a quartz tube, 2.0 m. long, 20 mm. inside diameter. On the left-hand side the tube is sealed in a vacuumtight manner by means of a concave ground aluminum block 2 (radius of curvature 4.5 m.) coated with a layer of gold 3.0. On the other side a flat germanium plate 4 (2 mm. thick) closes the tube.

The tube 1 is interrupted at 5 and 6 over a length of 0.5 mm.

the parts being connected by wider tubes 7 and 8. In the latter tubes, the platinum cylinders 10 are arranged at a distance of 0.5 mm. from the tube 1 and the elongations thereof. Tungsten lead-in members 11 and 12 support the electrodes. The 5 exhaust tube is denoted by 13.

FIG. 2 shows the right-hand part of the tube in a state in which it is not yet entirely finished. The tube 8 is sealed on the left-hand side to tube 1, the electrode 10 surrounds the copper cylinder 14, 0.5 mm. thick, which engages the tube. The elongation 16 of tube 1 is inserted on the right-hand side in the cylinder 14 until it engages the edge 15 which, from the cylinder 14, is directed inwardly and is enclosed between the tubes 1 and 16. The electrode 10 is previously welded to the lead-in member 12. After inserting the elongation 16, the sealing edge 17 may be formed. After dissolving the copper cylinder 14 in nitric acid, the tube may be finished.

What is claimed is:

1. A device for producing stimulated infrared emission comprising means including electrodes for providing an electric discharge in a discharge space containing a gas mixture consisting at least partly of carbonic acid in a circular-cylindrical quartz tube, said tube including circumferential interruptions, the electrodes being arranged laterally of the discharge space, said electrodes having the shape of circular-cylindrical rings arranged coaxially with said discharge space on the outside of said quartz tube and each surrounding a circumferential interruption, wider quartz tubes surrounding said electrodes and connecting the interrupted parts together in a vacuumtight manner.
2. A discharge tube for a device as claimed in claim 1 wherein the width of the interruption is a few tenths of a mm. and the electrodes surround the interruption with a distance of a few tenths of a mm. each of said electrodes being composed of platinum.
3. A device for producing stimulated infrared emission by means of an electric discharge in gas mixture comprising a circular cylindrically shaped quartz tube including first and second circumferential interruptions, first and second electrodes for providing said electric discharge, said electrodes each positioned laterally with respect to said tube and shaped as circular cylindrical rings arranged coaxially with said tube and surrounding a respective one of said circumferential interruptions, and means surrounding said electrodes and interconnecting the interrupted portions of said tube together in a vacuumtight manner.
4. The combination of claim 3 wherein each of said means surrounding said electrodes is a quartz tube.
5. A discharge tube for a device as claimed in claim 3, wherein the width of the interruption is a few tenths of a mm. and the electrodes surround the interruption with the distance of a few tenths of a mm., each of said electrodes being composed of platinum.
